UNITED STATES PATENT OFFICE.

HENRY P. G. STEEDMAN, OF LONDON, ENGLAND, ASSIGNOR TO VERPLEX ART COMPANY, INC., A CORPORATION OF NEW YORK.

PROCESS FOR THE REPRODUCTION OF OIL-PAINTINGS.

1,376,652.

Specification of Letters Patent.

Patented May 3, 1921.

No Drawing.

Application filed January 31, 1920. Serial No. 355,399.

To all whom it may concern:

Be it known that I, HENRY PERCY GORMANSTON STEEDMAN, a subject of the King of Great Britain, residing at London, in the county of London, England, have invented certain new and useful Improvements in Processes for the Reproduction of Oil-Paintings; and I do hereby declare the following to be a full, clear, and exact description of the invention, such as will enable others skilled in the art to which it appertains to make and use the same.

My invention consists in the novel features hereinafter described, and particularly pointed out in the claims, and is an improvement upon the process disclosed in my former Letters Patent of Great Britain #15,108 of 1911.

In the preparation of reproductions of oil paintings by the process disclosed in my former patent as ordinarily practised, a colored lithograph or other colored print on paper, of the painting to be reproduced, is applied to a piece of coarse canvas and the face of the print is painted over by hand, with a plastic material, which will readily harden, to produce raised portions following and corresponding with the brush marks and varying levels of the painted surface in the original painting. An embossing die is then formed from this prepared print usually by applying the prepared print under a great pressure to the surface of a plate of ebonite or other suitable substance capable of being rendered plastic by heat to receive the impressions both of the raised portions of the applied material on the face of the print and also of the grain of the canvas, the pressure applied being sufficiently great to impart both these variations of surface to the die. When the die has become hard it is used as an embossing die for the purpose of embossing other similar colored prints of the painting, whereby the irregularities are imparted to each print from the die and these colored embossed prints when varnished, present a remarkably accurate reproduction of an oil painting, and have the exact appearance, especially when varnished, of having been painted directly upon the canvas.

In carrying out this process the simulation of the brush markings upon the print from which the die is prepared requires a considerable degree of skill of an artist, and this very much increases the cost of such

reproductions. One of the objects of my invention is to dispense with this hand work in the preparation of the die, and to reproduce the irregularities of surface from an oil painting photographically and impart the same to the surface of the embossing die. Moreover the use of ebonite is attended with considerable disadvantages as it becomes extremely brittle, especially after repeated use, and is very likely to crack during use. Another object of my present invention is to form the embossing die of a plastic mass of treated casein which is more readily made to receive the impressions corresponding with the canvas, brush markings, etc., from the photographically prepared surface or plate before referred to than ebonite, and is free from the objections to ebonite, and at the same time is not inflammable, as are the compositions containing celluloid.

In carrying out my improved process, I first prepare photographically a surface provided with variations corresponding with the grain of the canvas and the various brush markings and variations in surface level of the painted portions. To this end I prefer to photograph the painting to be reproduced which may be an original painting, or a painted copy thereof, and the negative (or the positive therefrom) is placed upon a sheet of gelatin or other suitable material having incorporated with it sodium chlorid and a mucilage prepared from linseed oil, to which has been added a quantity of chrome alum sufficient to harden it, and suitable sensitizing material such as bichromate of potash and ammonia. The sensitized, gelatinized, sheet after exposure to the light, is developed by washing with water so as to remove those portions of the gelatinized sheet not affected by the action of light, and the gelatinized sheet is well washed, dried, and hardened, in any convenient manner, for example, by the application thereto of formaldehyde. I do not, however, limit myself to this particular photographic method, as any other photographic method which will produce a surface having the irregularities corresponding with the canvas grain and inequalities of the painted surface therein, may be employed. The sheet so formed, which for convenience of reference I term the matrix for the die, is used for the preparation of the embossing die, which may be formed of any desired

plastic material, or in any other known way. I prefer, however, to cast the embossing die by means of a plastic material prepared from casein, the said plastic casein being introduced into a frame inclosing the matrix, and being rolled therewith into sheet form and consolidated by pressure, and embedded in the photographically prepared surface of the matrix so as to receive the exact impression of the canvas grain, brush markings, etc., so photographically obtained directly from the original painting as before described. The die so formed is subsequently dried and hardened in any desired manner. From such a die colored prints of the painting can be embossed, as will be readily understood, and will impart to them the identical canvas grain and brush markings, and various inequalities of the painted surface, thereby obtaining a more perfect and accurate reproduction of the painting than can be obtained where the brush markings are applied by hand, and thereby dispensing with one of the most expensive items in the commercial production of such pictures.

The embossing dies may be so prepared as to operate upon either the face of the print or the back of the print, as preferred, in accordance with the manner in which the photographic matrix is obtained, and in some instances I may form both a male and female embossing die between which the prints can be embossed, where the use of such male and female dies is advantageous or desirable.

Plastic casein suitable for carrying out the invention may be prepared in various ways, for example, casein mixed with lime or other alkaline material is converted by the action of water into a plastic mass which dries so as to form a transparent hard elastic mass. I have also found that sulfonated rape oil may be mixed with dried powdered casein and kneaded into a homogeneous gelatinized mass, to which resin or caoutchouc and chalk or lime may be added, and the product hardened by vulcanizing with sulfur or exposing it to the action of formaldehyde. A solution of casein may also be mixed with a solution of resin and incorporated with lime, or any suitable vegetable or mineral ingredients, and hardened with formaldehyde. I may also obtain the casein plastic, by heating milk to 140° F., adding borax, and raising the temperature to 190°

F., in the presence of barium chloride or other mineral precipitant of casein. The washed precipitate is pressed and ground with an addition of acetic acid, soda, or other solvent, and the resulting mass is steam heated. Casein may also be made into a plastic mass with an aqueous solution of borax, the excess water removed, and a sufficiency of elastic nitrocellulose may then be added and the whole kneaded into a homogeneous mass.

I do not limit myself to the particular method of preparing the casein, it being only necessary to bring it into a plastic condition in which it can receive the impression from the matrix to reproduce the inequalities of surface thereof, and then to suitably harden it so that it may be used as an embossing die.

What I claim and desire to secure by Letters Patent is:

1. The herein described process for reproducing oil paintings, which consists in preparing photographically from an oil painting, a surface containing irregularities corresponding exactly to the identical canvas grain, brush markings and variations of surface levels of the original painting so photographically reproduced, applying to said photographic surface a plastic material, in such condition that it will enter all the marks and variations of surface, and forming an exact replica of said surface in said plastic, hardening the plastic material to form an embossing die, and embossing colored prints of said oil painting with said die.

2. The herein described process for reproducing oil paintings, which consists in preparing photographically from an oil painting, a surface containing irregularities corresponding exactly to the identical canvas grain, brush markings and variations of surface levels of the original painting so photographically reproduced, applying to said photographic surface a plastic material, consisting of plastic casein, in such condition that it will enter all the marks and variations of surface, and forming an exact replica of said surface in said plastic, hardening the plastic material to form an embossing die, and embossing colored prints of said oil painting with said die.

In testimony whereof I affix my signature.

HENRY P. G. STEEDMAN.
